UNITED STATES PATENT OFFICE.

RICHARD H. KRALI, OF CAMDEN, NEW JERSEY.

REFRIGERATOR.

1,254,513.

Specification of Letters Patent. Patented Jan. 22, 1918.

Application filed May 1, 1917. Serial No. 165,664.

To all whom it may concern:

Be it known that I, RICHARD H. KRALI, a citizen of the United States, residing at Camden, in the county of Camden and State 5 of New Jersey, have invented certain new and useful Improvements in Refrigerators, of which the following is a specification.

My invention consists of an improved refrigerator. One object of my invention is 10 to provide an improved refrigerator of the type which has chambers provided with front doors, said doors permitting the insertion of ice and food into their respective chambers.

Another object of my invention is to provide means within the refrigerator which will cause the air, chilled by the ice, to be purified and to be directed in an unobstructed path into the provision chambers and 20 then back again to the ice.

A further object is to provide improved means whereby the vapors, moisture, and impurities will be readily carried off with the drain water from the melting ice, leaving 25 pure, dry, and extremely cold air to pass in an unobstructed volume to the provision chambers.

A still further object is to so construct my improved refrigerator that it will not 30 contain any gutters or crevices thus avoiding the accumulation of slime or dirt.

Another object is to so make my refrigerator that it will be of simple construction and can be manufactured and sold at a 35 reasonable cost.

Another object is to so design certain of the parts that they can be easily and quickly removed for cleaning purposes.

These objects, and other advantageous 40 ends which will be described hereinafter, I attain in the following manner, reference being had to the accompanying drawings in which—

Figure 1 is a front elevation of a refrigerator constructed in accordance with my 45 invention.

Fig. 2 is an enlarged fragmentary section taken on the line 2—2 of Fig. 1.

Fig. 3 is a transverse fragmentary section 50 through a portion of the ice chamber and lower provision chamber illustrating certain of my improvements.

Fig. 4 is a view showing a corner portion 55 of the wall of my improved refrigerator prior to bending the same to form a sup-

porting ledge for certain of the elements hereinafter described.

Fig. 5 is a view of similar nature to Fig. 4 showing the same bend to provide the corner and ledge above noted.

Fig. 6 is a top plan view of a base plate which forms a part of my invention.

Referring to the drawings, 1 represents a refrigerator casing closed at the top, back, sides, and bottom, but open at the front as 65 will hereinafter be more clearly described.

An ice chamber 2 is normally closed by a door 3. This ice chamber is in communication with a chamber 4, directly below it, said chamber generally being used for the 70 storage of milk and butter and closed by a door 5.

A large vertically extending chamber 6 is separated throughout a portion of its length by a partition 7, and said chamber 6 is in 75 communication at its top with the ice chamber 2 through the medium of a passage 8. The chamber 6 is also in communication with the chamber 4 through the medium of a passage 9, so that air circulates downwardly through the ice chamber 2, chamber 4, passage 9, and thence upwardly through the chamber 6 and passage 8 into the ice chamber 2. The chamber 6 is normally closed by a door 10, and the doors above 85 mentioned can be of any of the usual type which are swung on hinges and provided with clasps whereby they can be securely held in a closed position.

The rear wall 11 and the side walls 12 90 and 13 of the chambers 2 and 4 are made of sheet material, preferably metal, and have inwardly bulged portions 14. These bulged portions are formed by cutting angular recesses 15 as clearly shown in Fig. 95 4, so that the sides and rear wall can all be made in one piece without any seams.

The top 16 of the bulged portion 14 forms a supporting ledge for the flange 17 of a frame 18, this frame having a depressed 100 portion 19 which is open at its bottom and provided with an internal flange 20 designed to form a support for a corrugated base plate 21, the latter having a plurality of perforations 22 as clearly shown in Fig. 6. 105

The front wall 23 is also preferably made integral with the side walls 12 and 13 and the top part 28 of its bulged portion is extended forwardly to provide a reinforcing facing 29 directly below the door 3. 110

The part 28 thus forms the support for the front flange 17 of the frame 18, it being understood that the ice is inserted through the front of the casing into the chamber 2 and rests upon the corrugated base plate 21.

A drip water tray 30 is suspended from the frame 18 by straps 31 and the bottom of the tray 30 is inclined and slants downwardly toward its rear end. A hole 32 is formed in said rear end and a spout 33 is secured to the bottom of the tray 30 in register with said hole 32. A drip pipe 34 is secured within the casing 1 and is of larger diameter than the spout 32 so that the latter 10 can slightly telescope the same. The lower end of the drip pipe 34 extends below the bottom 35 of the casing (see Fig. 2) and a pan may be placed below the drip pipe to receive the drip water passing therethrough.

Sheds 36 and 37 are preferably made of sheet metal and slant toward the tray 30. The ends 38 of the sheds 36 and 37 are secured to the straps 31 and extend directly over said tray 30. The sheds 36 and 37 adjacent their opposite ends are secured by straps 39 to the frame 18. I preferably extend the ends 40 of the sheds 36 and 37 beyond the outer surface of the depressed portion 19 of the frame 18 so that any moisture 15 which collects thereon will drop onto said sheds.

It will thus be noted that the sheds 36 and 37 are interposed between the bottom of the frame 18 and the tray 30, so that air currents are free to pass downwardly through the perforations 22 in the base plate 21, and downwardly toward the tray 30, coming in contact with the drain water so that any impurities will be absorbed by the water and carried out through the medium of the tray 40 30, spout 33, and drip pipe 34.

A deflector 41 is secured to the side and rear walls of the chamber 2 and has angularly disposed portions 42 and 43 on the side 45 walls, and an angularly disposed portion 44 on the rear wall. The portions 42 and 43 slant downwardly, as clearly shown in Fig. 2, toward the rear of the chamber 2 which permits the frame 18 together with its connection to be raised and removed through the front of the casing when door 3 is open. However, the portions 42 and 43 extend sufficiently far on the inside of the chamber 2 50 that any moisture which collects on the walls, will run down the upper surfaces, from thence it will drop into the frame 18, and eventually to the sheds 36 and 37 and tray 30.

In a similar manner, the portion 44 of the 60 deflector 42 will serve to deflect any moisture running down the rear wall 11, into the frame 18, and eventually into the tray 30 through the medium of the sheds 36 and 37.

Thus with my improved refrigerator, the 65 air chilled by the ice can freely circulate in

large volumes through the several chambers and the construction and disposition of the several parts is such that any impurities by coming in contact with the deflector, frame, sheds, and tray will be absorbed by the water 70 and carried directly to the drip pipe.

Therefore, by the construction above described, the air within the refrigerator will be kept pure, cold, and dry, thus rendering the refrigerator of particular value for 75 household or store purposes where various kinds of food are kept in the same refrigerator, since it will practically prevent one kind of food from being contaminated with the odor of another kind of food. 80

It will be further noted that by forming the supporting ledges integral with the walls which provide the inner lining of the casing, it will be practically free of crevices in which slime or other dirt can collect. The entire 85 frame, sheds, and tray can be removed as a unit, sufficient room being provided between the rear flange of the frame 18 and the portion 44 of the deflector 42 to permit the disconnection of the spout 33 with the drip 90 pipe 34.

While I have described my invention as taking a particular form, it will be understood that the various parts of my invention may be changed without departing from the 95 spirit thereof, and hence I do not limit myself to the precise construction set forth, but consider that I am at liberty to make such changes and alterations as fairly come within the scope of the appended claims. 100

Having thus described my invention, what I claim as new and desire to secure by Letters Patent is:

1. A refrigerator including a casing having an opening in one of its upright sides, a door for closing said opening, an inner wall made of sheet material having portions bent inwardly to provide a ledge substantially on a level with the bottom of said opening, a frame supported on said ledge and having a perforated bottom, and a deflector projecting inwardly from said wall sheet and having side portions extending at an angle downwardly on the side walls from portions adjacent said opening to the rear portion of 115 the wall and across the rear of said wall, substantially as described.

2. A refrigerator including a casing having an opening in one of its upright sides, a door for closing said opening, an inner wall made of sheet material having portions bent inwardly to provide a ledge substantially on a level with the bottom of said opening, a frame supported on said ledge and having a perforated bottom, a deflector projecting inwardly from said wall sheet and having side portions extending at an angle downwardly on the side walls from portions adjacent said opening to the rear portion of the wall, sheds supported below 120

125

130

said bottom of the frame and at opposite sides of the center thereof, and a water conducting tray supported below said sheds, said deflector being inclined sufficiently to 5 permit the forward ends of the frame and tray to be raised into a position to be bodily slid out of said opening in the casing, substantially as described.

3. A refrigerator including a casing having an angular interior and an opening in one of its upright sides, a door for closing said opening, an inner wall made of sheet material and being continuous around the angular portions of the interior of said casing, said wall having integral bulged por-

tions extending along the sides and back and located at a position between the top and bottom of the casing and providing a ledge at a level adjacent the bottom of said opening, and an ice supporting frame adapted 20 to rest upon said ledge, substantially as described.

In testimony whereof I have signed my name to this specification in the presence of two subscribing witnesses.
